UNITED STATES PATENT OFFICE

148,269

DESIGN FOR A TRAILER HITCH

Ralph W. Askins, Toledo, Ohio

Application July 19, 1946, Serial No. 131,704

Term of patent 7 years

(Cl. D14—6)

To all whom it may concern:

Be it known that I, Ralph W. Askins, a citizen of the United States and a resident of Toledo, Lucas County, Ohio, have invented a new, original, and ornamental Design for a Trailer Hitch, of which the following is a specification, reference being had to the accompanying drawing, forming a part thereof.

In the drawing:

Figure 1 is a rear perspective view of the trailer hitch showing my new design;

Figure 2 is a rear elevation of the trailer hitch;

Figure 3 is a side elevation of the trailer hitch; and

Figure 4 is a top plan view of the trailer hitch.

I claim:

The ornamental design for a trailer hitch, as shown.

RALPH W. ASKINS.
